(57) **CLAIM**

I claim the ornamental design for a delivery van, as shown and described.

DESCRIPTION

FIG. 1 is a top front perspective view of the delivery van according to the new design.

FIG. 2 is a bottom front perspective view of the delivery van shown in FIG. 1.

FIG. 3 is a top rear perspective view of the delivery van shown in FIG. 1.

FIG. 4 is a bottom rear perspective view of the delivery van shown in FIG. 1.

FIG. 5 is a front elevation view of the delivery van shown in FIG. 1.

FIG. 6 is a rear elevation view of the delivery van shown in FIG. 1.

FIG. 7 is a left side elevation view of the delivery van shown in FIG. 1.

FIG. 8 is a right side elevation view of the delivery van shown in FIG. 1.

FIG. 9 is a top plan view of the delivery van shown in FIG. 1; and,

FIG. 10 is a bottom plan view of the delivery van shown in FIG. 1.

The broken lines in the drawings illustrate portions of the delivery van that form no part of the claimed design.

1 Claim, 10 Drawing Sheets
